CONTAINER AND END CLOSURE THEREFOR AND METHOD OF MAKING

Bernard F. Sir, Benton Harbor, Mich., assignor to David Williams, Fred Williams, Edwin N. Williams, and John C. Williams, doing business as Williams Brothers, St. Joseph, Mich., a copartnership

Application October 12, 1942, Serial No. 461,713

8 Claims. (Cl. 229—5.5)

This invention relates to improvements in containers and end closures therefor and method of making.

The main objects of this invention are:

First, to provide an improved container formed entirely of fibrous stock in which the end closure, preferably the cover, may be repeatedly inserted and removed for opening and closing the container, and, although formed of relatively light stock, is sufficiently rigid to permit such manipulation.

Second, to provide an end closure for containers formed entirely of fibrous material which is strong and rigid and permits repeated handling or manipulations.

Third, to provide a method of forming end closures which enables the very rapid and economical production thereof.

Further objects and advantages pertaining to details and economies of construction and operation will appear from the description to follow. The invention is defined in the claims. Preferred embodiments of my invention are illustrated in the accompanying drawing, in which:

Fig. 1 is a side elevation of a container embodying the features of my invention partially in longitudinal section and partially broken away.

Fig. 2 is a top plan view of a modified form or embodiment of my invention.

Fig. 3 is an enlarged fragmentary view partially in vertical or longitudinal section of the embodiment of my invention shown in Fig. 2.

Fig. 4 is a plan view of the blank of the adjustable closure member of the embodiment of my invention shown in Figs. 2 and 3.

Fig. 5 is a longitudinal section through the blank or stock in the form of a tube from which the rim member of my improved end closure is formed.

Fig. 6 is a fragmentary sectional view illustrating one of the steps of forming the end closure.

Fig. 7 is a fragmentary view illustrating a succeeding step in the forming of the end closure of the embodiment of my invention shown in Fig. 1.

Fig. 8 is a slightly modified embodiment of the invention shown in Fig. 1.

In the accompanying drawing, the body of the container 1 is formed of fibrous stock, this being a tubular container. The bottom 2 is provided with a downturned peripheral flange 3 which is clampingly engaged by the inturned lower edge 4 of the container side wall. It will be understood, however, that the end closure of this invention, and which I will now describe, could be applied to both ends of the container.

My end closure of the embodiment shown in Fig. 1 comprises a disk-like wall member 5 of fibrous material and an annular rim member designated generally by the numeral 6, also

formed of fibrous material. This rim member has an intermediate cylindrical portion 7 adapted for telescoping engagement within the side walls of the container. The wall member 5 is inserted within this rim member which closely embraces the edge of the wall member. The inner end of the rim member is turned inwardly into a rounded bead-like portion 8 engaging the inner side of the wall member 5 while the outer end of the rim member is turned inwardly into a curved bead-like portion 9 which engages the wall member 5 in opposed relation to the inturned portion 8, thus securely clamping and supporting the wall member of the closure. The inturned portion 9 is joined to the cylindrical portion 7 by an outwardly offset portion 10 which constitutes an annular flange adapted to engage the end of the container when the closure is inserted therein, as shown in Fig. 1.

In the Figs. 5, 6 and 7, I illustrate certain steps of my method of manufacture. The disk-like wall members 5 are preferably died or cut from sheets of suitable container stock. The stock 11 from which the rim member is formed is cut from tubing formed of fibrous material of proper diameter for the particular container in which the end closure is to be used. This section or piece of stock 11 is positioned between die or forming members 12 and 13 with the end wall disk 5 in position in the rim stock and the dies actuated, preferably simultaneously, to form the clamping members 8 and 9 and the flange 10. This operation can be very rapidly performed and the closures produced are strong and rigid, even when formed of relatively light stock.

The disposition of the parts of the rim is such that the rim is made very rigid and the wall member is effectively supported therein. The end closures of this character may be repeatedly inserted and removed from the container and form a very close retaining joint therewith. Of course that involves the making of the end closures of proper diameter for the particular container in which they are to be used.

In Figs. 2, 3 and 4, I illustrate a modification of my invention in which the closure is provided with an adjustable closure member 14 disposed upon the closure wall member 15 for rotative adjustment. The members 14 and 15 have openings 16 and 17 therein adapted to be brought into or out of register for dispensing the contents of the container. In this embodiment, the wall member 15 is provided with a downturned peripheral flange 18, the lower end 19 of the rim member 20 being clamped around this flange 18 as shown in Fig. 3. The upper end of the rim member 20 is turned inwardly at 21 and conformed to provide the flange 22 substantially as described for the embodiment previously described. However, before the retaining bead 21

is formed, the disk-like closure member 14 is superimposed upon the closure wall member 15 and the bead 21 is so formed that it does not clamp the removable closure member so as to prevent its rotative adjustment. This clearance is illustrated in Fig. 3, but it will be understood that there is more clearance shown than would ordinarily be present.

The adjustable closure member 14 is formed of fibrous stock scored at 23 and 24 and notched at 25 to permit the folding of this scored portion into a handle or fingerpiece 26. The notches provide cut away portions 27 at the ends of the fingerpiece which permit the inturning of the bead 21. This embodiment of my invention is desirable for certain types of containers, particularly dispensing containers in which it is unnecessary to completely remove the end closure in order to afford access to the contents.

In Fig. 8 the wall member 15 has flange 18 also disposed with the flange upwardly. This provides a desirable structure when extra strength or rigidity is desired. While the closure can be easily inserted and removed, ordinarily without the aid of tools, it is at the same time very securely retained and provides an effective sealing closure.

I have illustrated my improvements in practical embodiments. I have not attempted to illustrate other embodiments which might be desirable to adapt my invention to particular types of containers, as it is believed this disclosure will enable those skilled in the art to embody or adapt my improvements as may be desired.

Having thus described my invention, what I claim as new and desire to secure by Letters Patent is:

1. The combination with a cylindrical container of fibrous material, of an end closure therefor, telescoping within the container and comprising a disk-like wall member of fibrous material and an annular rim member also of fibrous material closely embracing the edge of said closure wall member and having a substantially cylindrical intermediate portion frictionally fitting within said container, and inner and outer inturned end portions of rounded section disposed in opposed clamping supporting engagement with said closure wall member, the outer end portion being joined to said cylindrical intermediate portion by an outwardly offset portion constituting a wall engaging flange to position the closure within the container.

2. The combination with a container, of an end closure therefor telescoping within the container and comprising a disk-like wall member of fibrous material and a rim member also of fibrous material closely embracing the edge of said closure wall member and having an intermediate portion frictionally fitting within said container, and inner and outer inturned end portions disposed in opposed clamping supporting engagement with said closure wall member, the outer end portion being outwardly offset and constituting a wall engaging flange to position the closure within the container.

3. An end closure for telescoping within a container, comprising a disk-like wall member of fibrous material and an annular rim member also of fibrous material closely embracing the edge of said closure wall member and having a substan-

tially cylindrical intermediate portion for insertion within a container, and inner and outer inturned end portions of rounded section disposed in opposed clamping supporting engagement with said closure wall member, the outer end portion being joined to said cylindrical intermediate portion by an outwardly offset portion constituting a wall engaging flange to position the closure within a container.

4. An end closure for telescoping within a container, comprising a disk-like wall member of fibrous material and an annular rim member also of fibrous material closely embracing the edge of said closure wall member and having a substantially cylindrical intermediate portion for insertion within a container, and inner and outer inturned end portions disposed in opposed clamping supporting engagement with said closure wall member, the outer end portion being outwardly offset and constituting a wall engaging flange to position the closure within a container.

5. An end closure for telescoping within a container, comprising a wall member of fibrous material having an inturned flange at the periphery thereof, an annular rim member also of fibrous material embracing the said closure wall member and having a portion for insertion within a container, the inner end of said rim member being turned inwardly into clamping engagement with said flange on said wall member, the outer end of said rim member being outwardly offset to provide a container engaging flange to position the closure within a container and thence turned inwardly into a curved bead-like portion.

6. An end closure for telescoping within a container, comprising a wall member of fibrous material, a rim member also of fibrous material embracing the said closure wall member and having a portion for insertion within a container, the inner end of said rim member being turned inwardly and upwardly with its inturned edge in supporting engagement with said wall member, the outer end of said rim member being outwardly offset to provide a container engaging flange to position the closure within a container and thence turned inwardly into a bead-like portion.

7. The method of making end closures of fibrous material comprising the steps of forming a disk-like wall member of fibrous material and forming a tube of fibrous material, inserting the wall member within the tube and simultaneously turning the edges of the tube inwardly into inner and outer bead-like members of rounded sections with their edges in opposed clamping engagement with opposite sides of the wall member, and simultaneously with such last named step forming an outwardly projecting flange-like container end engaging portion on the outer bead-like member.

8. The method of making end closures of fibrous material comprising the steps of forming a disk-like wall member of fibrous material and forming a tube of fibrous material, inserting the wall member within the tube and turning the edges of the tube inwardly into inner and outer bead-like members with their edges in opposed retaining relation to opposite sides of the wall member, and forming an outwardly offset flange-like portion on the outer bead-like member.
